UNITED STATES PATENT OFFICE.

WILLIAM CHARLES GEBHARDT, OF LULING, TEXAS, ASSIGNOR OF TWO-THIRDS TO OTIS McGAFFEY, JR., AND CHARLES J. BUTFIELD, OF SAME PLACE.

PAINTING-MACHINE.

SPECIFICATION forming part of Letters Patent No. 504,833, dated September 12, 1893.

Application filed May 10, 1893. Serial No. 473,645. (No model.)

To all whom it may concern:

Be it known that I, WILLIAM CHARLES GEBHARDT, a citizen of the United States, residing at Luling, in the county of Caldwell and State of Texas, have invented new and useful Improvements in Painting-Machines, of which the following is a specification.

The object of my invention is to provide an automatic device for painting large surfaces which may be operated by an unskilled person, and it consists of a reservoir for the paint suitably connected with a paint brush to which is given a sweep similar to that of an expert painter by suitable mechanism actuated by the advance of the machine containing said reservoir and brush. The number of reservoirs and of brushes may be multiplied to suit convenience and the size of the machine. Where the paint does not flow readily to the brush or brushes, I provide an air pump connected with the reservoir to provide an internal pressure to force the paint through the connections. In the accompanying drawings I have shown this pump as driven by the advance of the painting machine, but it may also be operated by hand. When desired the painting machine may be preceded by a sweeping device removably attached thereto and followed by a smoothing or surfacing device also removably attached to the rear of the painting machine proper. Where of large size, the painting machine is provided with a canopy and automatic fan to protect the workman when driving the machine, a very necessary adjunct when painting roofs or other exposed surfaces in hot and sunny weather. Means are also provided for lifting and turning the painting machine.

In the accompanying drawings which illustrate my invention: Figures 1, 2, and 3 are plan views of the forward central and rear parts of my machine, with the canopy removed, showing in Fig. 1 the sweeper attachment with the forward end of the painting machine proper; in Fig. 2 the central part of the painting machine proper and in Fig. 3 the rear end of the latter, and the surfacing attachment. Figs. 4, 5, and 6 are side elevations of the same and Figs. 7, 8, 9, 10, 11 and 12 are views of various details.

A, Figs. 1 and 4, is the frame of the sweeping attachment secured to the frame, A', of the painting machine proper in any suitable way.

B is the dust box pivoted to the forward end of the frame A so as to have a vertical swing.

b is a rope or chain secured to the dust box tray B' at b', passing through eyes b², b³, in the sweeper frame braces a a² and extending back within reach of the operative who fastens it to the hook b³ on the frame A', Fig. 5, in order to hold the tray in position when sweeping, and releases it to lower and empty the box at the proper moment, as when the sweeper projects over the housetop which is being painted.

b⁴ is the projecting dust box lid or fender.

C is the roller dust brush of any suitable construction, carried in the pendent brackets C', in which its shaft c is vertically adjustable in any well known way. In the drawings the shaft c is shown adjustable by means of a series of apertures c' in the brackets C', which latter are securely braced to the sweeper frame A.

c² is the belt wheel keyed to the dust brush shaft c over which passes the driving belt C² connecting with a pulley C³ on the forward wheel G of the painting machine proper. 80

D is a splasher board fastened to a cross brace a' on the frame A and located behind the dust brush C to protect it from paint thrown by the brushes of the painting machine proper. The splasher board D is braced 85 to the cross piece a' by the small chain d which allows the board to yield to obstructions, as when passing over the seams on a tinned roof.

The construction of the painting machine proper is as follows:

E E', Figs. 1 and 4, are the forward paint brushes located across the front of the painting machine proper. Each brush consists of one or more parallel series of bristles (see 95 Fig. 7) e e', secured in a well-known way to the brush back E². The ends e² e³ of the brush back engage with slotted guides E³ on each side of the machine, suspended by brackets E⁴ secured to and adjustable vertically in 100

the frame A' in any well known way, in order to raise or lower the brushes in respect to the surface to be painted. In the drawings I have shown the brushes and guides vertically adjusted by means of bolts passing through the frame A' and apertures e⁴ in the brackets E⁴, but I do not limit myself to the same. A gage bar E⁵ at each end of the brush E' hooks over the bolt heads e⁵ on the corresponding ends of the brush E to hold them parallel and at suitable distance apart. The paint brushes E' E are reciprocated by means of the rods E⁶ connecting the brush E to the cranks f f of the crank shaft F which turns in the fixed bearings F' braced to the main frame A', (see Figs. 1, 2, 4, 5,) and to which the front wheels G of the painting machine are keyed. The front and rear ends e³ of the slotted guides E³ are turned up so as to lift and tilt the brushes at the end of each sweep before again bringing them in contact with the surface to be painted, and thus alternately presents each side of the brushes in the operation of painting, reproducing mechanically all the movements of an expert painter.

E⁷ E⁸ (Figs. 2 and 5) are the center paint brushes reciprocating in the slotted guides E⁹ and connected by rods E¹⁰ with the cranks f² f² of the crank shaft F², turning in the fixed bearings F³ braced to the main frame A' and to which the rear wheels G' of the painting machine are keyed; and E¹¹, E¹² (Figs. 3 and 6) are the rear paint brushes reciprocating in the slotted guides E¹³ and connected to the cranks f³ f³ of the crank shaft F² by the rods E¹⁴; the slotted guides E⁹ and E¹³ for each pair of brushes E⁷ E⁸ and E¹¹ E¹², as shown in the drawings, are formed in one piece suspended by the brackets E¹⁵ E¹⁶ from the main frame A' and adjustable vertically by bolts and apertures e⁴ in every respect similar to the adjustment of the forward brushes; but it is evident that the guides may be formed in two pieces independently adjustable if desired.

e⁶ and e⁷ are the gage rods between each set of brushes E⁷ E⁸ and E¹¹ E¹². It is thus seen that the rear crank shaft F² actuates two sets of paint brushes in every respect identical in their construction, connections and operation with the forward brushes; but that I may dispense with all of these and use but one reciprocating paint brush, its guide and suitable connections to which movement is imparted by the wheel of the painting machine proper to reciprocate the brush without in anywise departing from the spirit of my invention and irrespective of the manner in which the paint is supplied to the brush.

60 The mechanism for feeding paint to the paint brushes is constructed as follows:

H, Figs. 2 and 5, is the paint mixing cylinder which rests in the saddles h h firmly secured to the cross braces a³ a³ of the frame A' (Fig. 2). It is provided with handles h' h' by which it may be lifted on and off the saddle

h h to which it is fastened in any convenient and well known way.

H² is a funnel for filling the cylinder and has a screw threaded stopper h² to securely close the same, but any other well known device may be used.

H³ is the mixer stirrer of well known construction having keyed on the exterior end of its shaft h³ a driving wheel H⁴ over which passes the belt H⁵ driven by the pulley H⁶ keyed to the rear crank shaft F² of the machine.

H⁷, Figs. 2 and 5, is the paint cylinder below the level of the mixer cylinder and suspended at both ends in the stirrups h⁸ h⁸ hanging from the frame A' and wedged firmly in place by the removable inverted saddles H⁸ which fit over it and under the frame A'.

h⁷ h⁷ are handles for removing the cylinder H⁷, which is also provided with a stirrer H⁹ having its driving wheel mounted on the opposite end of the stirrer shaft and connected by belt and pulley to the forward crank shaft F of the machine on that side (not shown.)

I I are gages on the cylinders H H⁷ to determine the quantity of paint in each of them. In Figs. 2 and 5 I have shown the cylinder H⁷ formed in two sections bolted together at H¹⁰ in order that it may be taken apart for cleaning the interior; but all of the cylinders in the machine, as well as the mixer and paint cylinders H H⁷ may be constructed in any well known way in order to render the interior of the same accessible for any purpose.

J (Fig. 5) is a detachable pipe connecting the bottom of the mixer cylinder H with the interior of the paint cylinder H⁷, through which the paint flows from the former to the latter.

K, K, (Figs. 1 and 4) are flexible tubes which convey the paint from the paint cylinder H⁷ to the sprinkler K', Fig. 7, attached to the front paint brush E' below the brush back E² between the sets of bristles e e'. The sprinkler K' consists of a tube having a number of small apertures k through which the paint flows onto the bristles.

K², Fig. 7, is a valve for cutting off the supply of paint to the brush upon which it is mounted and consists of the hollow sleeve k' with which the supply pipes K and the sprinkler K' connect; and the valve spindle k² having the ports k³ which register with the pipe and sprinkler connections, when it is open; k⁴ is the handle for closing the valve. K⁵ are flexible pipes conducting the paint to a similar valve K² on the forward paint brush E.

K⁶ K⁷ are the tubes communicating with the central brushes E⁷ E⁸, Fig. 5, and K⁸ K⁹ (Fig. 6) the tubes connecting the rear paint brushes E¹¹ E¹² with the paint cylinder H⁷, shown only in part in the drawings; if required the paint may be cut off from the rear brushes E¹¹ E¹² which can then be used as smoothing brushes in place of the smoothing attachment described hereinafter.

In order to force the paint through the pipe connections I supply compressed air to the mixer cylinder H by means of the air pump L, Figs. 2, 5, and 9, mounted upon the painting machine, in which L' is the pump cylinder, L² the piston rod having a detachable pivot connection at l² with the driving rod L³ pivoted to the driving wheel l³ keyed on the end of the crank shaft F² of the rear wheels G'. L⁴ L⁴ are perforated caps through which the air enters the cylinder L' through the valves L⁵.

L⁶ is the compressed air chamber having the two valves L⁷. A coiled spring l⁸ abutting against the cross head of the inverted U-shaped valve guide l⁹ around the teat l⁸ and against the conical head of the valve L⁷ normally holds the latter down closing the port l⁴. A cross piece l⁹ having a central aperture forming a collar around the conical head of the valve, engages with the guide l⁹ on either side and slides up and down with the rise and fall of the valve.

l¹⁰ are rods which are screwed down upon the cross piece l⁹ in order to permanently close the port l⁴ when desired.

In Fig. 12 I have shown a modification of the locking attachment to the valve L⁷ in which the rods l¹⁰ pass through apertures l¹² on the cross piece l⁹ and are provided with upper and lower shoulders l¹³ l¹⁴ between which the cross piece rises and falls with the play of the valve. To lock the valve L⁷ down over the port l⁴ closing it, the rods l¹⁰ are screwed down until the upper shoulders l¹³ bear against the cross piece l⁹ the latter holding down the valve.

I do not limit myself to the particular construction of the valves shown, as any valve will answer my purpose which is adapted to be locked in position when required. The valves L⁵ are of similar construction except that the rod l¹⁰ is attached to the valve itself and projects through the perforated caps L⁴, through which it plays freely with the movement of the valve which is permanently closed by screwing down the nut l¹¹.

L⁸ is a communicating pipe between the compressed air reservoir L⁶ and the mixer cylinder H, opening near the top of the latter and out of the path of the stirrer H⁸.

L⁹ is a pipe connecting the cylinders H and H⁷ through which the air pressure may be admitted to the latter by opening the cock L¹⁰. Where the surface is ribbed as on a tinned roof I provide an additional attachment consisting of the brushes M, M, Figs. 2, 5, and 8, facing each other in order to paint each side of the rim or rib, and respectively secured to the two prongs of the forked hanger M' which is laterally adjustable along the cross piece M² by a bolt and bolt holes m to adjust the pairs of brushes to the distance between the ribs. A sprinkler M³ (Fig. 8) projects in front of each pair of brushes which may be two or more in number where it is firmly held by

one of the braces m³ which rigidly fasten the brushes to the hanger M'.

M⁴ is a valve to open and close the sprinkler and M⁵ the tube connecting it with the cylinder H⁷.

The brushes M⁹ M¹⁰ are independently attachable to the cross piece M², as shown in the lower set of brushes in Fig. 2, in order to adjust them to the width of the rib. The cross piece M² is rocked in bearings M⁶ by means of the hand lever M⁷ in order to raise and lower the brushes and sprinkler when desired.

M⁸ is a rack in which the lever M⁷ is locked when the brushes are raised.

N, Figs. 2 and 10, is a sprinkler rocking on journals n in bearings in the arms N' N' pendent from the frame A' in front of the central set of paint brushes E⁷ E⁸. It consists of the perforated tube N having a valve spindle N² with ports similar to those of the paint brush supply valves K² to open and close the sprinkler.

N³ is the valve handle.

N⁴ is the paint supply tube communicating with the paint cylinder H⁷.

N⁵ is an inclosing rim to hold the drippings when the sprinkler is rocked up.

N⁶ is the lever for rocking the sprinkler and N⁷ a catch to hold the lever.

The surfacing device which is rigidly attached to the rear of the painting machine proper consists of the frame A⁸ (Figs. 3 and 6) provided with front and rear bearings O O' for the journals O² O³ of the rotating drums 100 O⁴ O⁵ over which passes an endless canvas belt P to which is firmly riveted a series of transverse brushes P' having the construction shown in Fig. 11, in which each brush is surrounded with a rimmed pan p to catch the 105 drippings from the brush when the latter is inverted and thus keep the belt P clean. Endless chains Q Q communicate motion to the belt P by means of the sprocket wheels Q' on the rear crank shaft F² and the sprocket 110 wheels Q² on the drum journal O² to which they are respectively keyed.

The drums O⁴ O⁵ may be provided with cocks o⁴ o⁵ whereby they can be used for the storage of paint and turpentine.

R Fig. 5, is the handle by which the operative directs the movements of the entire machine as he walks on one side of it and pushes it along.

In order to turn the machine in the least possible space, I raise it entirely off the surface and pivot it on its center by means of the following device: S is a bar having a tripod foot s suspended by its piston head s' in the piston S' open at its upper end and firmly secured to the cross brace a' placed centrally across the machine frame. A coiled spring S³ surrounding the bar S within the piston abuts between the piston head s' and the bottom of the piston, and normally holds the foot 125 clear of the surface. In order to depress the foot and raise the machine, I pivot the lever 130

S^4 to the cross brace a^4 , the head of the lever bearing against a plunger S^5 in the open end of the piston. It follows that by raising the lever arm S^6 the plunger S^5 is forced down and with it the piston head s' compressing the spring S^3 and raising the entire machine off the surface.

S^7 is a toothed sector for locking the lever arm in place while turning the machine.

10 T Figs. 5 and 6, is the canopy frame over which the canopy is stretched.

U, Fig. 5, is a fan mounted in suitable bearings and over which passes the endless belt U^2 from the wheel U^3 keyed to the shaft U^4 which turns in suitable bearings in the frame T. Another belt U^5 passing over the pulley U^6 keyed to the same shaft and over the pulley U^7 on the forward crank shaft F of the machine communicates motion to the fan.

20 The front and rear wheels G, G' of the painting machine are laterally adjustable upon their respective crank shafts F, F², Figs. 1, 2, and 3, by means of the pins and bolt holes g on the crank shafts, the object being to set 25 the wheels to the width of the ribs on a tinned roof, which thus serve as guides or ways to direct the machine.

The operation of my machine is as follows: The mixer cylinder H being filled with the

30 proper ingredients and the sprinkler valves all opened, the machine is pushed along by the operative. The revolution of the wheels turns the cranks and drives the brushes, while the paint is forced through the various 35 connections by the air pressure produced by the air pump. At the end of each lap the machine is pivoted upon its foot, the sweepings from the dust pan having been discharged as described. When it is desired to clean the

40 pipe connection I shut off the valves L^7 and L^5 of the air pump L, and having filled the cylinder L' with turpentine or any suitable liquid, I detach the brush connections from the cylinder H⁷ and connect them with one 45 or the other of the cylinder cocks x y. I then detach the piston rod L² from its driving rod L³ and operate the piston rod by hand, forcing the contained liquid through the pipes and valves to clean them out. I thus provide

50 a compact and useful painting machine of simple construction, easily run by a single unskilled person, and capable of performing in a given time the work of a large number of skilled painters, thus effecting a great saving and economy of labor.

I do not limit myself to the detailed construction of my device, which may be greatly varied without departing from the spirit of my invention, but

60 What I claim as new, and desire to secure by Letters Patent, is--

1. In a traveling automatic painting machine, the combination with the bearing wheels of the machine, of a reciprocating paint brush adapted to alternately sweep back and forth over the surface to be painted, and suitable connections between the brush and the

said machine bearing wheels, for reciprocating the brush, substantially as described.

2. In a traveling automatic painting machine, the combination with the bearing wheels of the machine, of a reciprocating paint brush adapted to alternately sweep back and forth over the surface to be painted a device for vertically adjusting the brush, and suitable connections between the brush and the said machine bearing wheels for reciprocating the brush, substantially as described.

3. In a traveling automatic painting machine, the combination, with the bearing wheels of the machine, of a reciprocating brush adapted to alternately sweep back and forth over the surface to be painted, guides which direct the movement of the brush, and suitable connections between the brush and the said machine bearing wheels for reciprocating the brush, substantially as described.

4. In an automatic painting machine, the combination with a reciprocating paint brush, of adjustable guides which direct the movement of the brush, said guides having an upward curve at each extremity to raise and turn the brush and suitable connections between the brush and the machine wheels for reciprocating the brush, substantially as described.

5. In an automatic painting machine, the combination with a series of reciprocating paint brushes, having a spacing and connecting device between each brush and the next 100 of the series of adjustable guides which direct the movement of each brush of the series, said guides having an upward curve at each extremity to raise and turn the brushes, and a suitable connection between the series 105 of brushes and the machine wheels for reciprocating the brushes, substantially as described.

6. The combination with the frame A', of the crank shaft F, the wheels G keyed to the 110 shaft, the connecting rods E⁵ E⁶, the brush E', the slotted guides E³ engaging the ends e² e² of the brush back E², and the adjusting bars E⁴ supporting the guides and adjustably attached to the frame A', substantially as described.

7. The combination with the frame A', of the crank shaft F, the wheels G keyed to the shaft, the connecting rods E⁵ E⁶, the brush E', the brush E, the gage rods E⁵ connecting the 120 brushes, the slotted guides E³ engaging the ends e² e² of the brush backs E² of each brush, and the adjusting bars E⁴ supporting the guides and adjustably attached to the frame as described.

8. The combination with the frame A' of the crank shaft F², the wheels G' keyed to the shaft the connecting rods E¹⁰ E¹⁴, their respective sets of brushes E⁷ E⁸ and E¹¹ E¹², their respective gage rods e⁶ e⁷, their respective 130 slotted guides E⁹ E¹³ formed in one piece, and the adjustable guide supports adjustably attached to the frame A', as described.

9. The combination with the frame A' hav-

ing the crank shaft F, the wheels G keyed to the shaft, the connecting rods E⁵ E⁶, the brushes E' E, the gage rods E⁵ connecting the brushes, the slotted guides E³ engaging the ends e² e² of the backs E² of each brush, and the adjusting bars E⁴ supporting the guides and adjustably attached to the frame, of the crank shaft F², wheels G' keyed to the shaft, the connecting rods E¹⁰ E¹⁴, their respective sets of brushes E⁷ E⁸ and E¹¹ E¹², their respective gage rods e⁶ e⁷, their respective slotted guides E⁹ E¹³ formed in a single piece, and the adjustable guide supports E¹⁵ E¹⁶ adjustably attached to the frame, substantially as described.

10. The combination with the frame A', of the cross piece M² journaled in the bearings M⁶ secured to the frame A', brushes adjustable on the cross piece M², the lever M⁷ for raising the brushes and the rack M⁸ for locking the lever substantially as described.

11. The combination with the frame A', of the cross piece M², and the brushes M⁹ M¹⁰ facing each other and adjustable along the cross piece M², substantially as described.

12. In an automatic painting machine, the combination of a reciprocating paint brush, suitable connections between the brush and the machine wheels for reciprocating the brush, a receptacle for containing the paint, and suitable pipe connections between the brush and the paint receptacle for supplying paint to the brush, substantially as described.

13. In a painting machine, having a paint brush adapted to be automatically operated by the machine, the combination of a sprinkler on the brush, a paint receptacle and suitable pipe connections between the receptacle and the sprinkler to supply paint to the brush, substantially as described.

14. In a painting machine having a paint brush adapted to be automatically reciprocated by the machine, a paint receptacle, a paint distributor secured to and reciprocating with the brush, suitable flexible pipe connections between the receptacle for supplying paint to the distributor, an air pump actuated by the machine, and suitable pipe connections between the air pump and the paint receptacle, substantially as described.

15. The combination with an automatic painting machine having the reciprocating brush E' and suitable connections with the wheel G for reciprocating the brush, of the sprinkler K' located between the brush bristles, the paint cylinder H⁷, the flexible tube communication K between the sprinkler and the cylinder, a valve in said tube for closing the same, an air pump operated by the machine wheels, and pipe communication between the air pump and the cylinder, substantially as described.

16. The combination with a painting machine having the forward and central reciprocating brushes E' E, and E⁷ E⁸, and suitable connections with the wheels G' for reciprocating the brushes, of the sprinklers

located in the brushes, the paint cylinder H⁷, flexible tube communication between each brush and the paint cylinder, the valves 70 therein, the mixer cylinder H, the paint supply pipe J connecting the cylinders, the air pump L, its piston rod connection with the wheels G', its air pressure tube L⁸ communicating with the mixer cylinder H, the stirrers 75 H⁸ H⁹ located in the cylinders, their belt and pulley connections actuated by the wheels G G', the gages I on the cylinders, and means on the mixer cylinder H for filling the same, substantially as described.

17. The combination with a painting machine having brushes adapted to be automatically operated by the machine to paint a surface, of a set of laterally adjustable brushes located at an angle to the first brushes 85 and adapted to paint each side of a projection or rib on said surface, and suitable connections between each set of brushes and the machine, whereby both sets of brushes are simultaneously driven to paint an irregular 90 surface, as described.

18. In a painting machine, the combination with the laterally adjustable paint brushes mounted on the cross piece M² as described, of the reciprocating paint brushes E' E, and E⁷ E⁸, their adjustable slotted guides, suitable connections between the brushes and the wheels G' for reciprocating the same, the sprinklers on each brush, the paint cylinder H⁷, its tube communication with the several 100 sprinklers, the mixer cylinder H, its tubular connection with the cylinder H', the stirrers H⁸ H⁹, their belt and pulley communications with the wheels G' G', the gages I on the cylinders, and means on the mixer cylinder H 105 for filling the same, as described.

19. In a traveling painting machine having supporting wheels, the combination with a paint receptacle mounted thereon, of the standards N' secured to the machine frame 110 A', the sprinkler N journaled therein and having the drip rim N⁵, its valve and valve handle N² N³, the lever N⁶ for rocking the sprinkler, its catch N⁷ on the standard N', the pipe N⁴ for supplying paint to the sprinkler 115 connected to said receptacle, and an air pump actuated by the machine to force the paint to the sprinkler, substantially as described.

20. In a painting machine having brushes adapted to be automatically operated by the machine, a paint receptacle, detachable tubular connections between the paint receptacle and the brushes, and an air pump connected with the paint receptacle to force the paint through the connections, the combination 125 with the pump valves to cut off the communication of the pump with the paint receptacle and the air supply, and a cock to connect the pump directly through the detachable tube connections to the brushes, substantially 130 as described.

21. The combination with the frame A', of the cross brace a⁴, the piston S' secured to the same, the rod S provided with a suitable foot

- and having the piston head s' , the spring S^3 located in the piston between the piston head s' and the bottom of the piston, the plunger S^5 located in the piston, the lever S^4 pivoted to the cross piece and having its head bearing against the plunger S^5 , and the rack S^7 , substantially as described.
22. The combination with a traveling automatic painting machine having supporting wheels, of a detachable sweeper, driving gear for operating the sweeper and suitable connections between the supporting wheels of the painting machine, and the sweeper driving gear, substantially as described.
- 15 23. The combination with a traveling automatic painting machine having supporting wheels, of a detachable sweeper consisting of a vertically swinging box pivoted to the sweeper frame, a rotating roller brush, and suitable connections between the roller brush and the wheels of the painting machine, to actuate the brush, as described.
24. The combination with a traveling automatic painting machine having supporting wheels, of a detachable surfacing machine having driving gear and suitable connections between the supporting wheels of the painting machine and the driving gear of the surfacing machine, substantially as described.
- 25 25. The combination with a traveling automatic painting machine, of a detachable surfacing machine having supporting wheels consisting of a pair of drums turning in the machine frame, an endless belt passing over said drums and provided with suitable brushes, and suitable connections between one of the drums and the wheels of the painting machine to actuate the drum and move the endless belt, as described.
- 30 26. The combination with a traveling auto-

matic painting machine having supporting wheels, of a detachable sweeper having suitable driving gear, a detachable surfacer having suitable driving gear, and suitable connections between the supporting wheels of the painting machine and the respective driving gears of the sweeper and surfacing machines, substantially as described.

27. The combination with a traveling automatic painting machine having supporting wheels, of a detachable sweeper having a rotating roller brush, a detachable surfacer consisting of rotating drums having an endless brush belt driven by said drums, and suitable connections between the roller brush, the drums and the wheels of the machine to actuate the sweeper and surfacer, as described.

28. The combination with a traveling automatic painting machine having supporting wheels and driving gear to actuate the machine, of a fixed rotating axle having one or more of the supporting wheels laterally adjustable thereon, and suitable connecting mechanism between said driving gear and axle, substantially as described.

29. The combination with an automatic painting machine having moving parts, of laterally fixed rotating axles, suitable connecting mechanism between said axles and said moving parts and supporting wheels laterally adjustable upon said axles, substantially as described.

In testimony whereof I have hereunto set my hand in the presence of two subscribing witnesses.

WILLIAM CHARLES GEBHARDT.
